COIN OPERATED VENDING MACHINE

Emma A. Laughery, Chicago, Ill.

Application March 14, 1935, Serial No. 11,089
Renewed August 30, 1937

4 Claims. (Cl. 312—56)

This invention relates to an apparatus from which newspapers, periodicals or other selected commodities may be dispensed.

An object of this invention is to provide means for effecting the easy egress of a newspaper or other article from a vending machine when operated as intended, but which prevents the insertion of any implement through the delivery chute for withdrawing articles therethrough.

Another object is to provide an improved mechanism for lifting a single article with each actuation of the mechanism after release of the same on depositing the proper coin or coins.

Another object is to provide means for returning to the purchasers any coins inserted in excess of the ones called for.

Another object is to provide an improved form of pull device for operating a carriage which forms part of the dispensing mechanism.

Still another object is to provide means for closing the coin slot against the insertion of coins when operation of the dispensing mechanism has once been started.

These and other objects, as will hereinafter appear, are accomplished by this invention which is fully described in the following specification and shown in the accompanying drawings, wherein—

Fig. 1 is a perspective view of a coin operated vending machine for newspapers and the like;

Fig. 2 is an enlarged section on the line 2—2 of Fig. 1;

Fig. 3 is a detail in elevation of a pawl for lifting newspapers from the machine, the pawl being here shown locked in an inoperative position;

Fig. 4 is a similar view showing the pawl in operative position;

Fig. 5 is an end view of the needle shown on line 5 of Fig. 2;

Fig. 6 is an enlarged vertical elevation, partly in section, showing the coin chutes and associated parts; and

Fig. 7 is a fragmentary section on line 7 of Fig. 6.

My present invention is concerned with various features of improvement applicable to the type of vending machine which is shown and described in Patent No. 1,638,413, granted Aug. 9, 1927. Many details of construction there disclosed are therefore not repeated in the present drawings.

In the machine here illustrated I utilize a housing having a front wall 8, a rear wall 9, a bottom 10, end walls 11, and a hinged top 12 adapted to swing about a pivot 13 and to be suitably locked by a means not shown. A stack of

articles to be vended, such as newspapers A, are placed upon a suitable inclined runway 14, and these are pressed forward by a follower plate 15 to which are pivotally mounted rollers 15^a which operate on the runway 14. The plate 15 is further pressed by means of fingers 16, 17 which are urged forward by means of springs 18, 19, respectively.

These newspapers A or other commodities are pressed forward against a front plate 20 which carries a ledge 21 upon which the forward article rests. In front of the plate 20 are guides 22 whereon slides a carriage 23 (Fig. 2) to which is attached a chain 24 passing over a pulley 25. This chain is connected with a truck 26 which extends through a slot 27 in a guideway that is offset in the front of the housing. Preferably two pairs of rollers 28 are pivotally secured to the truck which rolls along the guideway upon opposite sides of the slot. An operating knob 29 connected to the truck extends through the slot to the front side of the machine housing. Thus it will be seen that the chain and associated parts are entirely closed within the housing with the exception of the operating knob so as to be protected against tampering and against the elements.

The lifting of the newspaper or other article, particularly when not too heavy, is accomplished, as in the patent above referred to, by means of a series of pins 30 which are carried upon a rock shaft 31, each of the pins operating in a slot 32 (Fig. 6). The method of mounting and operating these pins has been fully described in the above mentioned patent so that it will not here be repeated. One of the aspects of the present invention relates to the form of these pins. By making them pointed, tapered and of triangular cross section with the flat portion of the triangle on top (see Fig. 5) it is found that they are much more effective for lifting the articles without tearing or injury.

A vertical member 32^a (Figs. 2 and 6) is secured at each side of the housing and has a series of teeth on its front edge adapted to be engaged by a pawl (not shown) acting in a well-known manner to prevent the carriage from returning, once it has started, until the carriage reaches the upper limit of its travel.

For heavier articles, such as magazines, it may be desirable to supplement the pins with pawls 33 (Figs. 3 and 4), each of which is pivotally mounted on a pin 34 secured to the carriage 23. Each pawl is formed with an ear 35 extending from one side to engage the bottom of the car-

riage, whereby to serve as a limiting stop to the outward swing of the pawl into operative position, as shown in Fig. 4. Alongside each pawl lies a locking member 36 having a slot 37 through which passes the pin 34 so that the member 36 can be raised and lowered. A tension spring 38 connects a lug 36^a on the member 36 with a lug 33^a on each pawl. This spring urges the pawl 33 toward its operative position, and the member 36 toward the lowered position of Fig. 4. The member 36 also has a laterally extending lug 36^b which is adapted to engage a notch 33^b in the pawl, as shown in Fig. 3, to hold the pawl in an inoperative position.

15 It will be apparent that when a heavy article A' is to be vended, the lifting pawls 33 will be released so as to advance to operative position. At other times when lighter articles are to be dispensed, the pawls may be manually retracted and locked in the position shown in Fig. 3. Having raised the article and delivered it, as is explained in detail in the patent above referred to, the carriage returns by gravity and the pawls 33 pass down over the front of the next adjacent article, the springs 38 yielding sufficiently for this purpose.

In Figs. 6 and 7 the coin chutes are shown in detail. Thus the chute 39, 40 may be a penny chute, while the chute 41, 42 may be a nickel chute. The number of pennies to be taken through the penny chute may be adjustably fixed by the position of a coin adjusting lever 43 so as to receive no pennies, or one or more pennies. As shown in Fig. 6, this lever is adjusted to receive two pennies 44, and if another penny as 45 is inserted it will pass down an overflow chute 46 to a return chute 47 (Figs. 1 and 7) where the pennies will be returned to the outside whereby they are returned to the depositor. Similarly, if there be the insertion of a nickel 48 more than is required for the article to be vended, that nickel will be passed down the nickel overflow slot 49 to a return chute 50 (Figs. 1 and 6) for return to the depositor.

45 Another aspect of this invention relates to a means for closing the coin slot at the front of the box so that no more coins can be inserted after the carriage 23 has started its upward movement. To do this I have provided a lever 51 pivotally mounted at 52 which engages and is pressed down from the dotted line position to the full line position of Fig. 6 by means of a bearing 53, or other part of the carriage when the latter is down. The lever 51 is connected by means of a link 54 with a lever 55 near the top of the machine,

this lever being pivotally mounted at 56 and being normally urged toward the dotted line position by means of a spring 57; and formed on the lever 55 is an ear 55^a which closes the coin slot 58 at the point where coins are inserted so that no coin can be inserted therein so long as the ear 55^a is in the dotted line position corresponding to a raised position of the lever 51.

In order to protect the interior of this vending machine against the weather and tampering by the insertion of various instruments through the delivery slot, I have provided a shield 59 which is pivotally mounted on a pintle 60 (Fig. 2). In connection with the shield is a spring 61 tending to hold the shield in closed position, but permitting the shield to open in response to the movement of an article which is in process of being dispensed through the delivery slot 62. It will also be noted that the upper edge of this slot overhangs in such a way as to provide a 20 tortuous passage through which a straight object may not be inserted.

I claim:

1. In a dispensing machine, a pin adapted to be forced into an article to be dispensed, the pin having a point with a substantially flat leading surface adapted to exert a moving force upon the article without tearing it.

2. In a dispensing machine, a pin adapted to be forced into an article to be dispensed, the pin having a triangular point with a substantially flat leading surface adapted to exert a moving force upon the article without tearing it.

3. In a dispensing machine, a carriage, vertical guides for the carriage, a magazine for holding stacked articles to be dispensed, a pawl pivotally carried by the carriage, a spring for yieldably forcing the pawl into a position beneath the adjacent article whereby the pawl will lift the article when the carriage rises, and means utilizing the tension of said spring for locking the pawl in an inoperative position.

4. In a dispensing machine, a carriage, vertical guides for the carriage, a magazine for holding stacked articles to be dispensed, a pawl pivotally carried by the carriage, a spring for yieldably forcing the pawl into a position beneath the adjacent article whereby the pawl will lift the article when the carriage rises, and means for locking the pawl in an inoperative position, the spring being connected to the locking means so as to yieldably hold the locking means in a position to lock the pawl in an inoperative position.

EMMA A. LAUGHERY. 55
